ATTORNEY

UNITED STATES PATENT OFFICE.

JOHN P. COLEMAN, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-CAR RETARDER.

Application filed March 18, 1925. Serial No. 16,329.

My invention relates to railway car retarders, that is, to retarders for use in freight classification yards for controlling the speed of cars.

One object of my invention is the provision of improved automatic apparatus for controlling a car retarder in accordance with the weight of cars or the speed of cars or both.

I will describe one form of apparatus embodying my invention, and will then point out the novel features thereof in claims.

In the accompanying drawing, Fig. 1 is a plan view, partly diagrammatic showing one form of apparatus embodying my invention. Fig. 2 is a vertical sectional view showing the trackway illustrated in Fig. 1 and also showing one means for controlling the car retarder in accordance with variations in the weights of cars.

Similar reference characters refer to similar parts in each of the views.

Referring to the drawing, the reference character 1 designates a roadbed provided with track rails 2 and 2^a, along which cars move in the direction indicated by the arrow. The roadbed 1 is provided with a pit 3 containing a platform 4 which is so mounted as hereinafter explained that its vertical position varies in accordance with the weight which is on the platform. This platform carries track rails 2 and 2^a, which are in alignment with the rails 2 and 2^a on the roadbed 1, and the platform rails are provided with a car retarder D.

This car retarder D, in the form herein illustrated, comprises a pair of braking bars 5 and 6 located on opposite sides of the track rail 2, and a similar pair of braking bars 5^a and 6^a located on opposite sides of the other track rail 2^a. The braking bars for each rail are so associated with the rail that when they are moved toward the rail they will engage the wheels of a passing car and so will frictionally reduce the speed of such car. These braking bars are controlled by a fluid pressure motor B comprising two cylinders 7 and 7^a, containing pistons 36 and 36^a, respectively. These pistons are connected by means of links 37 with the braking bars 5, 6, 5^a and 6^a in such manner that when the pistons are moved outwardly each braking bar is moved to-

ward its associated track rail, and that when the pistons are moved inwardly to the positions in which they are shown in the drawing, each braking bar is moved away from its associated track rail.

Fluid pressure, usually air, is supplied to the motor B from a pipe line 35, which is connected with a source of pressure not shown in the drawing. Air is supplied to the inner end of each cylinder 7 and 7^a through a pipe 26, and the supply of air to this pipe is controlled by a valve device V^A. Air is supplied to the outer end of each cylinder through pipe 27, and the supply of air to this pipe is controlled by a valve device V^R. The valve device V^A is so constructed that the pressure admitted to the motor cylinders varies according to the strength of the current supplied to the controlling magnet of this valve; the particular form of valve device herein illustrated is described in detail hereinafter. The valve device V^R is a simple magnet valve which connects pipe 27 with the supply pipe 35 when the magnet of this valve is energized, but disconnects pipe 27 from pipe 35 and connects pipe 27 with the atmosphere when the valve magnet is de-energized.

Referring now to Fig. 2, the platform 4 is supported on two levers 32 and 32^a, which are pivotally mounted on beams 31 and 31^a, respectively. The inner ends of these beams are supported by a spring 33 which is seated on the floor of the pit. The construction is such that when the platform 4 is occupied by a comparatively heavy car, the spring 33 will be compressed to a considerable extent, so that the vertical downward movement of the platform will be comparatively great, whereas when the platform is occupied by a relatively light car compression of the spring 33 will be relatively less and the vertical downward movement of the platform 4 will likewise be relatively small. Pivotally attached to the lever 32 is a rod 11. This rod controls a variable impedance A^W associated with the circuit for valve device V^A, and for this purpose the rod is connected with an arm 10 pivotally mounted at a point 10^a. The impedance A^W is provided with a plurality of taps 9, which contact with the arm 10 in such manner that the heavier the car that occupies the platform 4

the less will be the amount of impedance A^W that is included in the circuit for the magnet of valve device V^A .

The reference character M designates an electric motor which operates a centrifuge C . This centrifuge in turn controls an arm 13 pivotally mounted at the point 13^a, so that as the centrifuge opens, due to increase in the speed of the motor M , the arm 13 is swung in counter-clockwise direction around its pivotal point. The arm 13 co-operates with taps 9 of a second impedance A^S in the circuit for valve device V^A , in such manner that the greater the speed of the centrifuge C , the greater will be the amount of the impedance A^S which is included in the circuit for the valve device V^A .

Extending to the right from the platform 4 is a track circuit T comprising a track battery 34 and a track relay R , the right hand limit of this track circuit being determined by insulated joints 8 in the track rails 2 and 2^a. The left hand limit of this track circuit is, of course, determined by the pit 3. The track battery 34 is directly connected across the rails in the usual manner, but the track relay R is connected across the rails through a contact 12 operated by the rod 11 in such manner that this contact is closed only when the platform 4 is unoccupied.

The motor M is controlled by a back contact 15-16 of relay R , so that this motor operates whenever the track circuit T is occupied by a car. The complete circuit for the motor M is from battery 14, through back contact 15-16, wires 18 and 19, motor M and wire 20 to battery 14.

The brake application circuit for fluid pressure motor device B is from battery 14, through back contact 15-16 of track relay R , wires 18 and 21, variable impedance A^S , arm 13, wire 22, arm 10, variable impedance A^W , wire 23, controlling magnet 39 of valve V^A , and wire 24 to battery 14.

The brake releasing circuit for the fluid pressure motor B is from battery 14, through front contact 15-17 of track relay R , wire 25, controlling magnet 50 of valve device V^R , and wire 24 to battery 14.

The valve device V^A , in the form here shown, comprises a Z-armature 38, which is controlled by the magnet 39, and which armature in turn controls a diaphragm 40. This diaphragm actuates two valves 41 and 42, which in turn control the fluid pressure in a chamber 43 to which the underside of the diaphragm 40 is exposed. These valves 41 and 42 are attached to a floating lever 44 provided with a stem 44^a, which engages the center of the diaphragm 40, that is, the point immediately under the point engaged by the stem 45 which is attached to the Z-armature 38. As the diaphragm 40 moves downwardly, it opens valve 41 to admit fluid pressure

from the pipe 35 to the chamber 43, and closes valve 42 to reduce the rate of exhaust from this chamber to the atmosphere. As the diaphragm moves upwardly, the operation is reversed, that is, valve 41 is closed to reduce the rate of supply of fluid pressure to the chamber 43, while the valve 42 is opened to increase the rate of exhaust from this chamber to atmosphere. The chamber 43 is connected by a pipe 46 with cylinder 47 containing a piston 48 which piston in turn controls a valve 49 interposed between the supply pipe 35 and the pipe 26. As the pressure in the chamber 43 increases, piston 48 is moved downwardly to increase the opening of valve 49, and so to increase the pressure supplied to the inner ends of the cylinders 7 and 7^a; as the pressure in chamber 43 decreases, the piston 48 moves upwardly to reduce the opening of valve 49 and so to limit the pressure supplied to the inner ends of the cylinders 7 and 7^a. The pressure in chamber 43 will vary in accordance with the strength of the current supplied to the magnet 39, and so the pressure supplied to the inner ends of the cylinders 7 and 7^a will likewise vary in accordance with the strength of the current supplied to the magnet 39.

The operation of the apparatus shown in Fig. 1, is as follows: As a car moving in the direction indicated by the arrow passes the insulated joints 8, it de-energizes the track relay R , thereby setting motor M into operation. As the speed of this motor and of the centrifuge C increases, the arm 13 will move upwardly, thereby progressively increasing the amount of the variable impedance A^S which is included in the circuit for the valve magnet 39. The position occupied by the arm 13 when the car enters the retarder D will therefore depend on the amount of time required for the car to pass from the insulated joints 8 to the retarder D , and will therefore depend on the speed of the car approaching the retarder. The parts are so designed that the amount of the impedance A^S which is included in the valve magnet circuit when the car enters the retarder D will vary inversely as the square of the speed of the car. When the car enters the retarder D the weight of the car will cause the arm 10 to move downwardly, whereby the amount of the variable impedance A^W which is included in the valve magnet circuit will be inversely proportional to the weight of the car. The amount of the current which is then supplied to valve magnet 39 will be determined by the two impedances A^W and A^S , and the amount of this current will be such that the braking effect of the retarder is sufficient to reduce the speed of the car to the desired value as the car leaves the retarder. While the car is on the platform 4, contact 12 will be opened

thereby keeping the track relay R de-energized. As the car leaves the platform 4, contact 12 will close, so that track relay R will then become energized. This will result in opening the application circuit and closing the releasing circuit for the fluid pressure motor B, so that the car retarder D will be restored to its normal condition.

It will be noted that while a car is on the retarder, motor M will continue to operate and that the centrifuge C would, consequently, cut into circuit all of the impedance provided. To prevent the latter (excepting for slowly moving cars) and to obtain a desired relation between car speed and reactance value, I preferably provide means for locking the arm 13 when a car enters upon the retarder, and during its presence there. As here shown, this locking means comprises a rack 28 fixed to the arm 13 and co-acting with a pawl 29 pivotally supported at point 29^a. This pawl 29 is operated by a link 30 attached to the arm 10, the operation being such that when the arm 10 moves downwardly in response to the weight of a car on the platform 4, the pawl 29 is shifted into engagement with the rack 28, thereby mechanically locking the arm 13 in the position which it occupies and so maintaining the reactance at the value that was determined by the speed of the car. The pawl 29 is preferably flexible, so that it will not be damaged by the excess movement transmitted to arm 10 by cars of greater weight than the minimum essential to such locking of the pawl.

As shown in Fig. 1, the source of current for the magnets of the valves V^A and V^R is a battery 14, so that in this form the impedances A^W and A^S are ohmic resistances. If alternating current is used for the control of the valve magnets, these impedances may be reactances.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a car retarder, and means controlled jointly by the weight of a car and by the speed of a car approaching the retarder for varying the braking effort exerted by the retarder.
2. In combination, a car retarder comprising braking bars mounted in the trackway for engagement with the wheels of a car, and means controlled by the weight of a car for varying the braking effort exerted by said retarder.
3. In combination, a car retarder, a circuit for the control of said retarder includ-

ing a variable impedance, and means governed by the weight of a car for varying said impedance.

4. In combination, a car retarder, a circuit for the control of said retarder including a variable impedance, and means governed by the speed of a car approaching said retarder for varying said impedance. 70

5. In combination, a car retarder, a circuit for the control of said retarder including two variable impedances, means governed by the weight of a car for varying one of said impedances, and means governed by the speed of a car approaching said retarder for varying the other impedances. 75 80

6. In combination, a car retarder, fluid pressure mechanism for operating said retarder, a magnet valve for varying the pressure admitted to said mechanism according to the strength of the current supplied to the magnet, a circuit for said magnet including a variable impedance, and means governed by the weight of a car for varying said impedance. 90

7. In combination, a car retarder, fluid pressure mechanism for operating said retarder, a magnet valve for varying the pressure admitted to said mechanism according to the strength of the current supplied to the magnet, a circuit for said magnet including a variable impedance, and means governed by the speed of a car approaching said retarder for varying said impedance. 95

8. In combination, a car retarder, fluid pressure mechanism for operating said retarder, a magnet valve for varying the pressure admitted to said mechanism according to the strength of the current supplied to the magnet, a circuit for said magnet including two variable impedances, means governed by the weight of a car for varying one of said impedances, and means governed by the speed of a car approaching said retarder for varying the other impedance. 100

9. In combination, a car retarder, fluid pressure mechanism for operating said retarder, a magnet valve for varying the pressure admitted to said mechanism according to the strength of the current supplied to the magnet, and means for varying the strength of the current supplied to said magnet in accordance with the weight of a car. 110

10. In combination, a car retarder, fluid pressure mechanism for operating said retarder, a magnet valve for varying the pressure admitted to said mechanism according to the strength of the current supplied to the magnet, and means for varying the strength of the current supplied to said magnet in accordance with the speed of a car approaching said retarder. 120

11. In combination, a car retarder, fluid pressure mechanism for operating said retarder, a magnet valve for varying the pres- 130

sure admitted to said mechanism according to the strength of the current supplied to the magnet, and means for varying the strength of the current supplied to said magnet in accordance with the weight of a car and its speed.

12. In combination, a platform mounted on a resilient medium whereby the vertical position of the platform varies according to the weight on the platform, a railroad track located on said platform and provided with a car retarder, and means for controlling said retarder in accordance with the vertical position of the platform.

13. In combination, a platform mounted on a resilient medium whereby the vertical position of the platform varies according to the weight on the platform, a railroad track located on said platform and provided with a car retarder, and means for varying the braking effort exerted by said retarder in accordance with variations in the vertical position of said platform.

14. In combination, a platform mounted on a resilient medium whereby the vertical position of the platform varies according to the weight on the platform, a railroad track located on said platform and provided with a car retarder, a variable impedance controlled by the vertical position of said platform, and a circuit including said impedance for controlling said car retarder.

15. In combination, a platform mounted on a resilient medium whereby the vertical position of the platform varies according to the weight on the platform, a railroad track located on said platform and provided with a car retarder, fluid pressure mechanism for operating said retarder, and means responsive to variations in the vertical position of said platform for governing said mechanism.

16. In combination, a platform mounted on a resilient medium whereby the vertical position of the platform varies according to the weight on the platform, a railroad track located on said platform and provided with a car retarder, fluid pressure mechanism for operating said retarder, a magnet valve for varying the pressure admitted to said mechanism according to the strength of the current supplied to the magnet, and means responsive to variations in the vertical position of said platform for varying the strength of the current supplied to said magnet.

17. In combination, a platform mounted on a resilient medium whereby the vertical position of the platform varies according to the weight on the platform, a railroad track located on said platform and provided with a car retarder, fluid pressure mechanism for operating said retarder, a magnet valve for varying the pressure admitted to said mechanism according to the strength of the current supplied to the magnet, and a circuit for

said magnet including a variable impedance controlled by the vertical position of said platform.

18. In combination, a car retarder, a circuit for the control of said retarder including a variable impedance, a centrifuge for controlling said impedance, and a motor for operating said centrifuge.

19. In combination, a car retarder, a circuit for the control of said retarder including a variable impedance, a centrifuge for controlling said impedance, a motor for operating said centrifuge, and means for setting said motor into operation when a car approaching said retarder passes a fixed point.

20. In combination, a car retarder, a centrifuge, means for rotating said centrifuge at a variable speed determined by the speed of a car approaching said retarder, and means for controlling said retarder in accordance with the speed of rotation of said centrifuge.

21. In combination, a car retarder, a centrifuge, means for rotating said centrifuge at a variable speed determined by the speed of a car approaching said retarder, a variable impedance controlled in accordance with the speed of rotation of said centrifuge, and a circuit including said impedance for controlling said retarder.

22. In combination, a car retarder, a centrifuge, means for rotating said centrifuge at a variable speed determined by the speed of a car approaching said retarder, fluid pressure mechanism for operating said retarder, and means responsive to the speed of said centrifuge for governing said mechanism.

23. In combination, a car retarder, a centrifuge, means for rotating said centrifuge at a variable speed determined by the speed of a car approaching said retarder, fluid pressure mechanism for operating said retarder, a magnet valve for varying the pressure admitted to said mechanism according to the strength of the current supplied to the magnet, and means responsive to the speed of said centrifuge for varying the strength of the current supplied to said magnet.

24. In combination, a car retarder, a centrifuge, means for rotating said centrifuge at a variable speed determined by the speed of a car approaching said retarder, fluid pressure mechanism for operating said retarder, a magnet valve for varying the pressure admitted to said mechanism according to the strength of the current supplied to the magnet, and a circuit for said magnet including a variable impedance controlled by the speed of said centrifuge.

25. In combination, a car retarder, a circuit for the control of said retarder including a variable impedance, a centrifuge for controlling said impedance, a motor for

operating said centrifuge, and means for preventing variation of said impedance while a car is passing through said retarder.

26. In combination, a car retarder, a motor, means for setting said motor into operation when a car approaching said retarder passes a given point, a centrifuge operated by said motor, an arm controlled by said centrifuge, a variable impedance controlled by movement of said arm, a circuit for said retarder controlled by said impedance, and means for locking said arm while a car is passing through said retarder.

27. In combination, a platform mounted to move vertically in response to the weight of a car, a railroad track located on said platform and provided with a car retarder, a motor, means for setting said motor into operation when a car approaching said retarder passes a given point, a centrifuge operated by said motor, an arm controlled by said centrifuge, a variable impedance controlled by movement of said arm, a circuit for said retarder controlled by said impedance, and means for locking said arm while said platform is occupied by a car.

28. In combination, a car retarder, a track circuit for controlling said retarder, and a contact included in said track circuit and controlled by the weight of a car.

29. In combination, a car retarder, a track circuit for controlling said retarder, and means for keeping said track circuit open while a car is passing through said retarder.

30. In combination, a platform mounted to move vertically in response to the weight of a car, a contact closed when said platform is unoccupied but open when the platform is occupied by a car, a railroad track located on said platform and provided with a car retarder, and a track circuit located in advance of said platform for controlling said retarder and including said contact.

31. In combination, a car retarder, a track circuit located in advance of said retarder and including a track relay, a releasing circuit for said retarder controlled by a front contact of said relay, and an application circuit for said retarder controlled by a back contact of said relay.

32. In combination, a car retarder, fluid pressure mechanism for operating said retarder, a magnet valve for varying the pressure admitted to said mechanism according to the strength of the current supplied to the magnet, a track circuit located in advance of said retarder and including a track relay, a motor set into operation when said track relay becomes de-energized, a centrifuge operated by said motor, a variable impedance controlled by said centrifuge, a second variable impedance responsive to the weight of a car while passing through said retarder, and a circuit for said magnet in-

cluding said two impedances in series and a back contact of said track relay.

33. In combination, a car retarder, a track circuit located in advance of said retarder and including a track relay, a motor set into operation when said track relay becomes de-energized, a centrifuge operated by said motor, a variable impedance controlled by said centrifuge, a second variable impedance responsive to the weight of a car while passing through said retarder, an application circuit for said retarder including said two impedances in series and a back contact of said track relay, and a releasing circuit for said retarder controlled by a front contact of said track relay.

34. In combination, a platform mounted on a resilient medium whereby the vertical position of the platform varies according to the weight on the platform, a railroad track located on said platform and provided with a car retarder, a variable impedance controlled by the vertical position of said platform, a track circuit located in advance of said platform and including a track relay, a motor set into operation when said track relay becomes de-energized, a centrifuge operated by said motor, a variable impedance controlled by said centrifuge, an application circuit for said retarder including said two impedances in series and a back contact of said track relay, and a releasing circuit for said retarder controlled by a front contact of said track relay.

35. In combination, a platform mounted on a resilient medium whereby the vertical position of the platform varies according to the weight on the platform, a railroad track located on said platform and provided with a car retarder, a variable impedance controlled by the vertical position of said platform, a track circuit located in advance of said platform and including a track relay, a motor set into operation when said track relay becomes de-energized, a centrifuge operated by said motor, a variable impedance controlled by said centrifuge, fluid pressure mechanism for operating said retarder, a magnet valve for varying the pressure admitted to said mechanism according to the strength of the current applied to the magnet, and a circuit for said magnet including said two impedances in series, and a back contact of said track relay.

36. In combination, a car retarder, a track circuit located in advance of said retarder and including a track relay, a motor set into operation when said track relay becomes de-energized, a centrifuge operated by said motor, a variable impedance controlled by said centrifuge, and a circuit for said car retarder controlled by said impedance.

37. In combination, a car retarder, a motor, means for setting said motor into operation when a car approaching said retarder

passes a given point, a centrifuge operated by said motor, a variable impedance controlled by said centrifuge in such manner that as the centrifuge opens in response to 5 motor speed the impedance is progressively increased, fluid pressure mechanism for operating said retarder, a magnet valve for varying the pressure admitted to said mechanism according to the strength of the current supplied to the magnet, and a circuit 10 for said magnet controlled by said impedance.

38. In combination, a car retarder, a motor, means for setting said motor into operation when a car approaching said retarder 15 passes a given point, a centrifuge operated by said motor, a variable impedance controlled by said centrifuge in such manner that as the centrifuge opens in response to 20 motor speed the impedance is progressively increased, a second variable impedance controlled by the weight of a car passing through said retarder in such manner that the greater the weight the less the value of 25 the impedance, fluid pressure mechanism for operating said retarder, a magnet valve for varying the pressure admitted to said mechanism according to the strength of the current supplied to the magnet, and a circuit 30 for said magnet including said two variable impedances in series.

39. In combination, a car retarder, a variable impedance, means for varying said impedance in accordance with the weight of a car passing through the retarder in such

manner that the greater the weight the less the value of the impedance, fluid pressure mechanism for operating said retarder, a magnet valve for varying the pressure admitted to said mechanism according to the 40 strength of the current supplied to the magnet, and a circuit for said magnet controlled by said variable impedance.

40. In combination, a car retarder, a fluid pressure motor for operating said retarder, 45 a second fluid pressure motor for releasing said retarder, two valves one for controlling the application of fluid pressure to each of said motors, means controlled by the speed and weight of a car for governing one of 50 said valves and other means not controlled by the speed or weight of a car for governing the other of said valves.

41. In combination, a car retarder, a fluid pressure motor for operating said retarder 55 and a second fluid pressure motor for releasing said retarder, a magnet valve for varying the pressure admitted to said first motor according to the strength of the current supplied to the magnet, a second magnet valve 60 for controlling the admission of pressure to the second motor, means for varying the strength of the current supplied to the magnet of said first valve in accordance with the speed and weight of a car, and means not 65 responsive to the speed and weight of the car and supplying current to the magnet of said second valve.

In testimony whereof I affix my signature.
JOHN P. COLEMAN.
